UNITED STATES PATENT OFFICE.

WILLIAM C. HAMMOND, OF SAULT STE. MARIE, ONTARIO, CANADA.

PICKET SHARPENER AND SHAPER.

1,108,167.

Specification of Letters Patent.

Patented Aug. 25, 1914.

Application filed December 1, 1913. Serial No. 804,021.

To all whom it may concern:

Be it known that I, WILLIAM C. HAMMOND, a citizen of the United States, residing at Sault Ste. Marie, in the Province of Ontario and Dominion of Canada, have invented a new and useful Picket Sharpener and Shaper, of which the following is a specification.

The present invention appertains to a 10 picket sharpener and shaper, and aims to provide a novel and improved device of that character.

It is the object of the present invention to provide an attachment for a jointer or planing table, and which shall be so constructed and operable, as to enable fence pickets, and the like, to be readily sharpened and shaped by the cutter of the jointer or planing table.

Another object of the present invention is 20 to provide a mechanism of the nature indicated which shall be adjustable to accommodate various widths and thicknesses of pickets, and in order that the pickets may be sharpened or shaped as desired.

It is also within the spirit of the present invention, to provide an appliance of the character specified, which will be comparatively simple, durable and inexpensive in construction, as well as simple, convenient, 30 practical and efficient in its use.

With the foregoing and other objects in view which will appear as the description of the invention proceeds, the invention resides in the combination and arrangement of parts and in the details of construction hereinafter described and claimed, it being understood that changes in the precise embodiment of the invention herein disclosed can be made within the scope of what is claimed 40 without departing from the spirit of the invention.

The invention has been illustrated in its preferred embodiment in the accompanying drawings, wherein—

Figure 1 is a side elevation of a jointer or planing table, illustrating the present device applied thereto, portions being broken away. Fig. 2 is a plan view of the parts depicted in Fig. 1, a portion of the eccentric handle being broken away. Fig. 3 is a sectional view taken on the line 3—3 of Fig. 1, illustrating the attachment in end elevation. Fig. 4 is an enlarged sectional detail taken on the line 4—4 of Fig. 1.

In the drawings, the numeral 1 designates an ordinary or arbitrary jointer or planing

table, the top of which is provided with a transverse opening 2 in which the cutter 3 works, the cutter 3 being mounted on a rotary shaft 4 driven by belt power, or the like. The cutter 3 has its blades so arranged, as to work upwardly through the opening 2, slightly above the plane or face of the top of the jointer or table frame.

The present attachment embodies a base plate 5, disposed upon the top of the jointer or planing table adjoining the opening 2, and equipped along one edge, with a longitudinal upstanding flange 6. The base plate 5 is adjustable longitudinally upon the jointer frame, to and from the cutter shaft 4, and to this end, the base plate 5 is provided with a longitudinal slot 7, and the top of the jointer frame is provided with a pair of upstanding stud bolts 8 passing through the slot 7, and bearing thumb or clamping nuts 9 for maintaining the base plate 5 at any position to which it is slid. That end of the flange 6, adjoining the opening 2, or the forward end of the flange, is provided with an upright portion or standard 6^a having a slot 10 above the cutter 3.

A carrier plate 11 is disposed snugly against the outer side of the flange 6, and at its forward end has a shouldered clamping bolt 12 which engages therethrough, and passing through the slot 10 of the standard 6^a. The bolt or fulcrum member 12 is adapted to pivot the carrier plate 11 to the standard, and when loosened, is adapted to permit the carrier plate 11 to be adjusted vertically. The carrier plate 11 extends away from the opening 2 and is provided along its lower edge, with a flange or ledge 13 adapted to rest upon the top of the jointer frame, and serving as a seat or rest for the picket 14, the picket 14 being placed on edge on the flange or ledge 13 and resting flatly against the carrier plate 11.

At the outer or rear end, the carrier plate 11 supports a plate 15, a clamping bolt 16 being engaged to the plate 15 and passing through a longitudinal slot 17 in the rear end portion of the carrier plate 11, and a thumb or clamping nut 18 being engaged on the bolt 16 to clamp the plate 15 at any adjusted position. The plate 15 is provided at its forward end with a flange 19 serving as a seat or rest for the rear end of the picket 14. A handle 20 is attached to the inner face of the carrier plate 11 adjoining its rear end, as seen most clearly in Fig. 2.

As a means for holding the picket 14 upon the flange or ledge 13, an eccentric 21 is pivoted to the carrier plate 11 intermediate its ends, and is provided with a handle or lever 22 projecting rearwardly. The handle or lever 22 carries a supplemental or auxiliary holding means, embodying a vertical slotted strip 23, and a clamping screw 24 engaged through the slot thereof and taking into the handle or lever 22, the lower end of the strip 23 being bent angularly to form a foot 25 adapted to rest upon the upper edge of the picket.

In the operation of the sharpener and shaper attachment, the picket 14 is placed 15 upon the flange or ledge 13, flatly against the carrier 11, and the end rest 15 is adjusted properly along the rear end portion of the carrier 11, according to the length of 20 the picket. After the picket is thus positioned, the handle 22 is depressed, whereby the eccentric 21 clamps the picket upon the ledge 13, or if the picket is unusually narrow, the holder 23 may be let down and 25 clamped by means of the set screw 24, so that the foot 25 and holder 23 engages the upper edge of the picket to hold the picket in place. The forward end of the picket projects over 30 the carrier 11 and flange 6 terminating short of the cutter. After the picket has thus been applied to the carrier 11, the handles 20 and 22 are grasped by the operator, and 35 the carrier 11 is swung upwardly, as indicated by the dotted lines in Fig. 1, which will cause the forward end of the picket to be swung downwardly into engagement with the cutter 3, the carrier 11 swinging about the bolt 12 as a center or fulcrum. Thus, 40 the lower edge portion of the forward extremity of the picket is cut away upon a curved line or arc, as indicated in dotted lines in Fig. 1. The carrier 11 is then swung against the jointer frame top, and the picket 45 is reversed, in order that the forward portion of the other edge of the picket may be rounded as above described to complete the sharpening of the picket.

From the foregoing it will be apparent 50 that the present device will accommodate pickets of various lengths, thicknesses and widths. Attention is also directed to the fact that the base plate 5 may be adjusted longitudinally to and from the shaft 4 of 55 the cutter, whereby the end of the picket may be sharpened or shaped in various manners, and furthermore, the fulcrum or pivot bolt 12 may be adjusted vertically for variance in the cutting of the end of the picket.

60 The present device may not only be employed for sharpening and shaping pickets, but may be employed for sharpening or shaping sprags, stakes, and other wooden

articles. The present attachment is comparatively simple, and may be readily applied to an ordinary jointer or planing table, or to any other suitable mechanism embodying a convenient cutter.

With the present appliance, the pickets may be readily applied to the same, and operated upon, and then removed, the entire operation being carried out in a simple and expeditious manner.

Having thus described the invention, what is claimed as new is:

1. The combination with a table having an opening, and a cutter working within the opening, of an attachment comprising a base plate mounted on the table adjoining the opening, a fulcrum member carried by the base plate above the cutter, a carrier fulcrumed to the fulcrum member and extending away from the said opening, and means carried by the carrier for holding a picket with its end protruding above the cutter for engagement therewith when the carrier is swung away from the table.

2. The combination with a table having an opening, and a cutter working within the said opening, of an attachment comprising a base plate adjustably mounted upon the table to move to and from the said opening, the base plate having a standard above the cutter, a fulcrum member vertically adjustable along the standard, a carrier fulcrumed to the fulcrum member and extending away from the said opening, and means carried by the carrier for holding a picket with its end protruding above the cutter, whereby the end of the picket will engage the cutter when the carrier is swung upwardly away from the table.

3. The combination with a table having an opening, and a cutter working within the opening, of an attachment comprising a base plate mounted upon the table adjoining the said opening, and having a longitudinal upstanding flange, a fulcrum member carried by one end of the said flange above the cutter, a carrier plate disposed adjacent the said flange, one end of the carrier plate being fulcrumed to the said fulcrum member, and the carrier plate extending away from the said opening, the carrier plate having a lower ledge forming a picket rest, and clamping means carried by the carrier plate above the said ledge for holding a picket thereon with one end of the picket projecting over the cutter.

In testimony that I claim the foregoing as my own, I have hereto affixed my signature in the presence of two witnesses.

WILLIAM C. HAMMOND.
